Primary Examiner — Ian Simmons*Assistant Examiner* — Samantha Q. Lawrence(74) *Attorney, Agent, or Firm* — William E. Gallagher; Dara M. Kendall(57) **CLAIM**

The ornamental design for an absorbent article with a pattern, as shown and described.

DESCRIPTION

FIG. 1 is a perspective view of an absorbent article with a pattern;

FIG. 2 is a front view thereof;

FIG. 3 is a rear view thereof;

FIG. 4 is a right side view thereof; and,

FIG. 5 is a left side view thereof.

The broken lines shown in the drawings illustrate portions of the absorbent article with a pattern that form no part of the claimed design.
